UNITED STATES PATENT OFFICE.

GEORGE R. PYPER, OF MIDVALE, UTAH.

TIME-CONTROLLED SWITCH.

1,221,216.

Specification of Letters Patent. Patented Apr. 3, 1917.

Application filed January 17, 1916. Serial No. 72,591.

To all whom it may concern:

Be it known that I, GEORGE R. PYPER, a citizen of the United States, residing at Midvale, in the county of Salt Lake and State of Utah, have invented certain new and useful Improvements in Time-Controlled Switches; and I do declare the following to be a full, clear, and exact description of the invention, such as will enable others skilled in the art to which it appertains to make and use the same.

My invention which relates to improvements in time-controlled switches has for its object to provide a device of this class which may be simply and easily manufactured and marketed, and which may be used for either completing or breaking an electric circuit at a certain predetermined time.

With this general object in view, the invention resides in certain novel features of construction and unique combinations of parts to be hereinafter fully described and claimed, the descriptive matter being supplemented by the accompanying drawings, which constitute a part of this application and in which:

Figure 1 is a rear elevation of an alarm clock showing parts of the invention associated with the alarm winding shaft thereof; Fig. 2 is a rear elevation of the clock with parts in section, showing more particularly the arrangement of the circuit closing and breaking member and the operative and dummy contacts with which it co-operates.

Fig. 3 is a fragmentary view similar to Fig. 2, showing different positions of parts;

Fig. 4 is a horizontal sectional view as seen on the plane of the line 4-4 of Fig. 2 looking in the direction indicated by the arrows; and

Fig. 5 is vertical sectional view taken on the plane indicated by the line 5-5 of Fig. 2.

In specifically describing the invention shown in the drawings above briefly described, similar reference characters will be placed on corresponding parts throughout the several views and reference will be herein made to the numerous elements by their respective indices. To this end, the numeral 1 designates a well known type of alarm

clock having the usual alarm winding shaft 2 which extends rearwardly through the alarm bell 3, the latter substantially covering the back of the clock as shown.

Mounted loosely on the shaft 2 and confined within the bell 3, is an insulating block 4 to which an elongated circuit closing and breaking member 5 is secured by a pair of rivets or the like 6, said member being constructed of any suitable kind of metal and having a central opening through which the shaft 2 passes without contact. The ends of the rivets 6 remote from the block 4 are surrounded by sleeves 7 of insulating material 85 for a purpose to appear.

The opposite ends of the member 5 are formed with female contacts 8 adapted for co-operation with a pair of operative male contacts 9 or with a single dummy contact 9^a, the three contacts 9 and 9^a being spaced upon an arc described around the shaft 2 as clearly shown in Figs. 2 and 3. The contacts 8, 9 and 9^a are so constructed as to cause considerable friction to exist when the first named contacts are engaged with any of the others, this friction, however, being overcome at the proper time.

Secured at one end to the insulating block 4 and at its other end to the shaft 2, is a spring 10 which may be of any preferred design. Thus, when the shaft 2 is rotated by the interior mechanism of the clock at a predetermined time, the frictional engagement of the member 5 with the contact or contacts with which it is engaged will hold said member against movement momentarily. However, rotation of the shaft will now place the spring 10 under tension, and if this tension be great enough, it will overcome the frictional engagement above mentioned and will suddenly shift the member 5 as desired. In order to assist the spring 10 in its operation, however, the sleeves 7 and a tappet 11 have been provided, the tappet being secured to the shaft as clearly shown in Fig. 2. By this arrangement, while the spring 10 is under tension, the tappet 11 will strike one of the sleeves 7 and will thus start the member 5 from the contact or contacts frictionally retaining the same.

In the present embodiment of the invention, a pair of current conducting wires 12 and 13 are shown as connected with the fixed operative contacts 9, these wires being connected with a number of electric lights 14 as shown in diagram in Fig. 2. As is usual, a thumb switch 15 is provided whereby the lights may be controlled manually. When the lights are to remain illuminated until a certain time, the switch 15 is turned off as shown in Fig. 2 and the member 5 is set manually (by means to be described) in the position disclosed in said figure, the alarm of the clock having been set at the proper time. Thus, when this time is reached and the shaft rotates in the direction of the arrows in Fig. 1, the spring 10 will be placed under tension and the moment the tappet 11 forces downwardly on the left hand sleeve 7, the frictional engagement between the contacts 8 and 9 will be overcome and the spring will shift the member 5 to the position shown in Fig. 3, wherein one of its contacts 8 is frictionally engaged with the dummy contact 9a. The rotation of the shaft 2 is now checked by contact of its winding key 16 with a stop pin 17 carried by the bell 3, said key having moved from the full line position shown in Fig. 1 to the dotted line position while the operation above described has taken place. When now, the member is to be again set as shown in Fig. 2, the key 16 will be turned in a clockwise direction, thus rewinding the alarm spring, the movement of the key in this direction being limited by a stop pin 18. If the invention is to be used for closing the circuit of the lights at a predetermined time, the member 5 is set as shown in Fig. 3, but the key 16 is moved counter-clockwise past the stop 17, this being allowed by pivoting said key to the shaft as shown. Thus, when said shaft 2 rotates the necessary amount, the member 5 will be suddenly shifted from its engagement with the dummy contact 9a into contact with the two devices 9, whereupon the circuit of the lights 14 will be completed. The movement of the shaft 2 during this operation, will be limited by a third stop pin 19 as shown by the dot and dash lines in Fig. 1.

As clearly shown in the several figures of the drawings, the key 16 extends in opposite directions from the shaft 2 for engagement with the numerous stops 17, 18 and 19 as occasion may demand, the pivotal connection between the key and the shaft being such as to allow said key to be tilted to an extent great enough to clear the intermediate stop 17, but the stops 18 and 19 are of such a length as to prevent movement of the aforesaid key past the same.

From the foregoing description, taken in connection with the accompanying draw-

ings, the construction, manner of operation and numerous advantages of the improved switch mechanism will be readily understood without requiring a more extended explanation. In conclusion, however, I wish to state that although the invention is shown applied in the circuit of a number of electric lights, its application need not be limited to this use. Furthermore, I have shown numerous structural details for illustrative purposes, and above have described such details. It is manifest, however, that numerous changes may be made within the scope of the appended claims.

I claim:

1. In combination, a manually set time-controlled rotary shaft, a circuit closing member mounted thereon to be limited to a number of movements, a trio of stops spaced on an arc described around the shaft, and a hand key having a portion extending laterally from the shaft for contact with said stops, said key being pivoted to said shaft to allow it to be rocked manually in order to clear the intermediate stop.

2. In combination, a time-controlled rotary shaft, a circuit closing member mounted thereon to be limited to a number of movements, and means for limiting the rotation of said shaft to one movement, said means being releasable manually to permit further movement of the shaft.

3. In combination, a time-controlled rotary shaft, a circuit closing member mounted thereon to be limited to a number of movements, a plurality of stops spaced apart on an arc described around the shaft, and a stop member carried by and extending from the shaft for engagement with said stops, said stop member being movably mounted to allow it to be manually shifted to clear one of said stops, thereby allowing further movement of the shaft.

4. In combination, a time-controlled rotary shaft, a pair of operative contacts spaced apart on an arc described around said shaft, a dummy contact also disposed on said arc, a double-ended circuit closing member mounted on said shaft and adapted to be manually set in engagement with the operative contacts, whereupon rotation of the shaft at the predetermined time will break the circuit and engage the aforesaid member with the dummy contact, and stop means for limiting this movement of the shaft, said means being manually releasable to permit the next rotation of the shaft to again engage the circuit closing member with the operative contacts to complete the circuit.

5. In combination, a time-controlled circuit closing member movable along a predetermined path and serving to complete an electric circuit at either end of said path,

and means for limiting the movement of said member to a point between the ends of the path, whereby the circuit will remain broken, said means being manually releasable to allow the next movement of the circuit closing member to again complete the circuit.

In testimony whereof I have hereunto set my hand in presence of two subscribing witnesses.

GEORGE R. PYPER.
